UNITED STATES PATENT OFFICE.

JAMES D. FRARY, OF NEW BRITAIN, CONNECTICUT.

IMPROVEMENT IN MANUFACTURE OF KNIVES AND FORKS.

Specification forming part of Letters Patent No. 58,242, dated September 25, 1866.

To all whom it may concern:

Be it known that I, JAMES D. FRARY, of New Britain, county of Hartford and State of Connecticut, have invented certain new and useful Improvements in the Manufacture of Knives; and to enable others skilled in the art to make and use the same I will proceed to describe its peculiarity by referring to the drawings, in which the same letters indicate like parts in each of the figures.

The nature of this improvement will be understood from the specification and drawings. The object desired to be attained thereby is to unite or secure the bolster in one piece of metal in its proper place upon the shank of the blade, and to secure the handle (made in two parts) to the shank by (metal bars) the same means by which the bolster is secured.

In the accompanying drawings, Figure 1 shows a knife in a finished state. Fig. 2 shows an edge sectional view of the blade with the bolster secured thereto. Fig. 3 shows an edge sectional view of a blade, having a two-part handle secured thereto.

a is the blade. *a'* is the shank. *a''* is the bolster. *c* is the material which forms the handle proper. *d* are connections or gripping-bars. The blade *a*, with its shank, is first made in the usual way. The holes through which the molten metal passes are made somewhat larger than what are made where the bolster and handle are secured by rivets. Then the shank is tinned by the common way of tinning, for the purpose, first, so that the molten metal will adhere thereto in the act or process of forming the bolster thereon, whereby the bolster itself and the bolster and blade become one firmly-united piece of metal; or, in other words, the bolster is formed on the blade in one piece of metal, and not only so, but so that it may properly be said that the bolster and the blade or shank are one piece of metal; and, second, to prevent rust from forming on the surface and edge between the surface of the handle and the shank, which is commonly seen in knife and fork handles now in use, giving a very dingy unwholesome appearance thereto. This tinning is not necessary to the carrying out of the main principle

of this invention, but it is believed will essentially improve the article both in appearance and utility.

To effect this improvement, (forming the bolster in one piece of metal on the shank,) proper molds are prepared, (which may be done in several different ways familiar to a practical person,) so that the blade or the shank of the blade, with or without the parts of the handle, may be placed therein, and the molten metal poured therein. Thus it will be clearly seen that by placing the blade or the shank of the blade, tinned or untinned, into a properly-formed mold, either with or without the parts which make up the handle, the bolster will be perfectly formed in one piece of metal onto the blade; and, further, that when the handles with the shank of the blade are placed true in a proper mold they may also be secured at the same time, and by the same means, of pouring molten metal bars *d* into places prepared therefor, which, in cooling, firmly gripe the handles together on the shank.

In this way I am enabled to make a knife having a solid bolster formed on each side and connecting together through an opening in the blade or shank in one piece of metal, and having a handle secured thereon without riveting, thus producing a neat, tasteful, and desirable article of manufacture.

I believe I have thus shown the nature and mode of proceeding to effect this improvement.

What I claim, therefore, and desire to secure by Letters Patent, is—

1. Forming a bolster, *a''*, upon a blade, *a*, having perforations in the center thereof, through which the metal is poured to form a solid bolster, substantially as described.

2. Securing the handles *c*, made in two parts, having holes therein to correspond with those formed in the blade, and countersunk, so that the metal poured therein will firmly gripe the parts together, substantially as described.

JAS. D. FRARY. [L. S.]
